(57) **CLAIM**

The ornamental design for a display screen with graphical user interface, as shown and described.

DESCRIPTION

FIG. 1 is a front view of a display screen with graphical user interface, showing a first embodiment of the new design; FIG. 2 is a second embodiment thereof; and, FIG. 3 is a third embodiment thereof.

The broken line showing of the display screen with the graphical user interface is included for the purpose of illustrating portions of the article and forms no part of the claimed design.
